SUCCESSIVE NON-INTERFERENCE SIGNAL-BOX.

1,210,398.

Specification of Letters Patent.

Patented Jan. 2, 1917.

Application filed August 11, 1913. Serial No. 734,226.

To all whom it may concern:

Be it known that I, CLARENCE E. BEACH, a citizen of the United States, residing at Binghamton, in the county of Broome and State of New York, have invented a new and useful Improvement in Successive Non-Interference Signal-Boxes, of which the following is a specification.

Non-interference and succession signal boxes heretofore devised have been found to require the use of mechanism to avoid the exhaustion of their motive power, and designed to operate on one or the other of the following principles: the restoring principle, applied to arbitrarily stop and restore the box to its normal locked position when, after it has been pulled, it has made a predetermined number of attempts to transmit its signal; the stopping principle, applied to suspend the running of the train when the box determines, after being pulled, that the circuit is disabled.

In the application of the restoring principle, it is obviously needful that, to be effective, it must restore the box before it has so far exhausted its motive power that, after having been so restored, if pulled again without being rewound, there will remain sufficient motive power to operate the box for a second like period without thereby completely exhausting the motive power. On the other hand, it is equally obvious that restoring mechanism arranged to so act curtails the effectiveness of the succession function of any box to which it is applied by greatly curtailing the time, after being once pulled, that it will remain in condition to transmit its signal. The balancing of these two considerations has resulted in the general practice of adjusting the boxes heretofore equipped with restoring mechanism so that after a run which, had the box been fully wound at the start, would about half exhaust the motive power, the restoring mechanism will become effective. Thus, such a box would at one time completely exhaust its motive power without accomplishing any useful purpose, merely because it happened to be pulled a couple of times when its circuit was disabled and the very same box would also fail to send its signal at another time after having uselessly half exhausted its motive power, merely because

its circuit happened to be occupied with other signals until about the time the restoring mechanism acted.

In the application of the stopping principle to which I have referred, neither of the foregoing considerations applies, but the pulling of a box equipped with such a stopping mechanism at a time when its circuit was disabled will result in such box retaining the signal until its circuit is restored, so that its signal may thus be transmitted hours or even days after the box was pulled, and when the need for its transmission has ceased to exist.

Non-interference and succession boxes have also heretofore been devised with a view of securing the transmission of their signals through a ground connection to be rendered effective by the running of the box if the metallic circuit remained broken a predetermined time after one of such boxes was pulled; but these former boxes have rarely, if ever, been used in actual service, because of disadvantages, the most prominent of which are the following:—The ground connections of such boxes have been so applied that only one-half of the non-interference magnet winding has been effective when such boxes were utilizing their ground connection for the transmission of their signals over one side of a broken circuit, in spite of the fact that the circuit resistance over one side of the line and through such grounds as are ordinarily available at signal boxes is apt to be substantially greater than the normal metallic circuit resistance. Such former boxes have been arranged to continuously apply their ground connection at all times when their signaling contacts were closed, so that if two boxes were pulled in one leg of a broken circuit and the box nearest the central office applied its ground connection before the more distant box had transmitted its signal, the restoring mechanism of the more distant box would act to stop that box before it could transmit its signal, unless the box nearer headquarters completed its signal and disconnected its ground during the effective portion of the run of the more distant box, subsequent to the establishment of its ground connection.

One of the objects of this invention is to

provide a non-interference, succession and emergency ground connection signal box which, when acting to transmit its signal through its ground connection, will furnish frequent opportunities for any more distant 5 box to determine whether it may establish circuit therethrough so that such distant box need not cease to attempt the transmission of its signal unless its portion of such 10 circuit shall remain deenergized for a period longer than the longest period between such ground removals.

Another object of this invention is to automatically so apply such an emergency 15 ground connection that the line current will pass through all windings of the non-interference magnet while the box is transmitting its signal, regardless of whether over an all-metallic or a grounded return 20 circuit.

Other objects of this invention are to provide a form of such a signal box which will be positive and effective in action and which is adapted to be more economically manufactured and will require less skilled supervision than other boxes for like purposes heretofore devised; and other objects are described in the following specification and more particularly pointed out in the claims.

In constructing this invention I provide means for securing at frequent intervals during the transmission of the signal of the box through its emergency ground connection, closures during only a fraction of each 25 of which the ground connection is effective, but I do not limit myself to the construction of this means which I have shown and hereinafter describe, nor to the use of the other features of my invention in combination with this means, as it is evident 30 that the features of my invention are susceptible to many changes in construction and arrangement, and insertion or omission of parts, and to be applied to various other 35 forms of signal boxes, either separately or in combination with each other, without departing from the spirit of my invention.

For applying the emergency ground connection, I provide mechanism, which, for 40 brevity, I will hereinafter call "a circuit changer," which is so arranged that when in one position the metallic circuit through the box is not altered by said circuit changer, but when said circuit changer occurs 45 a second position, the metallic circuit is grounded at one side of the box, and when said circuit changer is in a third position, the metallic circuit is grounded at the other side of the box, this circuit changer 50 being adapted to be so applied to a signal box that it will be moved by the train in running, subject to the control of the non-interference magnet so that if, after the box 55 is pulled, the non-interference armature remains in retracted position for a predeter-

mined period longer than the longest deenergized period incident to the transmission of the signal of any box, said circuit changer will act to apply a ground connection to the metallic circuit at one side of its 70 box; and if thereupon the non-interference magnet becomes energized, such ground connection will be maintained until the box is brought to rest as the result of having transmitted an effective signal, but if, during the 75 running of the train, the non-interference armature remains in retracted position for a further predetermined period longer than the longest period of deenergization of its circuit incident to the transmission of the 80 signal of any box, such circuit changer will act to transfer the ground connection to the other side of its signal box.

A means is provided, constantly tending to restore the circuit changer to the position 85 in which the metallic circuit through the box is not altered by said circuit changer.

This improved circuit changer is adapted to be so applied to the detent controlling structure of various types of well-known 90 non-interfering and succession signal boxes, that such detent will be caused or permitted to act to stop the box and cause the restoration of the parts of said box to normal condition whenever the circuit changer has 95 been moved to a predetermined point by the train in running, and the non-interference armature has remained in retracted position during such running of said train for a predetermined period longer than the longest 100 period of deenergization of its circuit incident to the transmission of any signal.

For the purpose of preventing the return of the circuit changer after it has been moved to apply the ground connection to either side of the box, upon the attraction of the non-interference armature, I provide a holder which permits the circuit changer to be moved by the train in one direction to suitably apply said ground connection, 110 and is adapted to prevent the movement of the circuit changer in reverse direction to an extent which will change the circuit conditions, while permitting such slight movement of the circuit changer in reverse direction as will prevent its further movement by the running of the train, in the event of the attraction of the non-interference armature; said holder being adapted to be rendered ineffective when the detent 115 is in position to stop the train, so that when the detent acts to cause the restoration of the other parts of the box, said holder will be rendered ineffective.

In constructing this circuit changer, I 120 provide a member moved by the train in running, subject to the control of the non-interference magnet and adapted to be so utilized that if, during the running of the train, the non-interference armature remains in re- 125

tracted position for a predetermined period longer than the longest period of deenergization of its circuit incident to the transmission of the signal of any box, such member will act to cause stopping and restoration of the mechanism of its box.

For the purpose of more clearly illustrating this invention, I have shown its application to one type of signal box in the accompanying drawings, like figures of reference referring to the same parts throughout, in which:

Figure 1 shows a front elevation of the essential parts of a box embodying this invention, the front plate being removed, the better to show the mechanism; Fig. 2 is an enlarged view of a portion of Fig. 1; Fig. 3 is a diagrammatic view showing the circuits of the box, Fig. 4 a ground connection which may be used at a receiving station, and Figs. 5 and 6 are views of parts of the mechanism at different stages of operation.

In Fig. 1, the main gear 1 is suitably driven by a spring not shown. This gear 15 engages pinion 2 on intermediate shaft 3 which bears a gear 4. This gear engages pinion 5 on signal wheel shaft 6 which bears a gear 7, which engages pinion 8 on escape wheel shaft 9 which bears an escape wheel 20 10 which engages a pallet 11. The signal wheel 12 is adapted to engage the breaker arms 13, 14 to control the signaling circuit. These breaker arms are similar to those shown in the patent to H. W. Doughty and 25 C. E. Beach, No. 949,699, dated Feb. 15, 1910, with an addition to arm 13, which is shown more clearly in Fig. 2 and which will be hereinafter explained. The starting mechanism consists of a detent 15, adapted 30 10 to be lifted by the disengaging means 16. The detent has a lug 17 which engages a notch in the flange 18 on the gear 4. The detent normally holds the train against the tension of the main spring so that when the 35 detent is raised the train is released and will run until stopped. Controlling structure is provided for the detent and, in this particular embodiment of my invention, consists of the following parts: A plate 19, used as a 40 prop for the detent 15 is loosely mounted on the shaft 3 and is provided with two sets of ratchet teeth 20 and 21, a radial edge 22 and a circumferential edge 23. A spring 24 is attached to the framework and bears upon 45 plate 19 tending to rotate the plate to the left. A pin 25 on the detent 15, when the train is held by the lever, lies to the left of the radial edge 22 on the plate 19 and holds 50 the plate in the position shown. When the 55 detent 15 is lifted, the armature of the non-interference magnet being retracted, the spring 24 will throw the plate to the left until the projection to the left of the ratchet teeth 21 hits the pin 25. Another plate 26 is secured to shaft 6 and is provided on its un-

der side with a pin 27, used to restore the plate 19 to its normal position. At each rotation of shaft 6 the pin 27 is adapted to engage the teeth of ratchet 21 when the latter is in its abnormal position, moving it a distance equal to one tooth at each revolution.

A pawl 28 is mounted on the framework in the path of the teeth of ratchet 20. This pawl is provided with an extension which engages a pin 29 on the armature lever 30 which bears the armature 31 of the non-interference magnet 32. The object of the

plate 19 and the pin 27 is to secure four consecutive revolutions of the signal wheel when the box gets control of the line: When 30 the non-interference armature is retracted, pin 29 has moved pawl 28 clear of ratchet 20 and operation of the disengaging means will lift detent 15, allowing plate 19 to move to the left and permitting the train to 35 run. If now the magnet should become energized the pawl 28 will engage the teeth of ratchet 20 separately and consecutively as the plate 19 is moved by the pin 27 until the plate has been moved far enough to allow 40 the pin 25 to drop off the edge 23, whereupon the detent 15 will enter one of the notches in the flange 18 and stop the train.

This controlling structure may also be operated after a certain length of time, if the box 45 does not have a chance to send its signal, by a ratchet wheel 40 mounted loosely on the shaft 3, a pawl 41 mounted on the framework, and the plate 26 secured to the shaft 6, which plate at the beginning of each revolution of the shaft 6 is adapted to engage the ratchet wheel 40 and advance it one tooth. The ratchet wheel is normally held under the tension of restoring means consisting of a spring 42 and the pawl 41 is pivoted at 43 50 and has an upwardly extended end which lies in the path of pin 29 on armature lever 30. When the line is open the pawl 41 is thrown into engagement with the ratchet wheel 40 to thereby hold the ratchet against 55 backward rotation as it is rotated forward step by step by the plate 26. When the line is closed the pawl is disengaged from the ratchet, permitting it to return to normal position. A pin 45 is so mounted upon 60 wheel 40 that after said wheel has been moved one tooth at a time for a sufficient number of revolutions of the shaft 6 and held by retaining pawl 41, said pin 45 will strike the plate 19 and move it clockwise to a 65 point where it will permit the detent to move to normal position and thereby stop the train.

The pin 33 is mounted on lever 30 to engage the catch 34 loosely pivoted at the end 70 of breaker arm 13. As shown in Fig. 2, which is a back elevation of the end of arm 13, the catch is held against the pin 35 by the spring 36. The lower end of the catch 34 is so beveled that when the pin 33 is brought 75

against said bevel by the pull of the retractile spring applied to the non-interference armature the pressure of said pin on such beveled surface will raise the arm 13 sufficiently 5 to permit said pin 33 to pass under the end of the catch 34, but the form of the face of said catch above its beveled end is such that the pressure of the pin 33 against said face will not cause the arm 13 to be raised. When 10 the armature moves to retracted position the pin 33 passes under the end of catch 34, thus lifting said catch and the arm 13 slightly until said pin 33 has passed to the right of the end of said catch 34 (Fig. 1) whereupon 15 the arm 13 will drop slightly so as to bring the end of said catch into the path of said pin whereby said pin retains control of and holds the breaker arm 13 up. While the arm 13 is supported by the first tooth of the 20 signal wheel the pin 37 on gear 7 strikes the pin 38 extending backwardly from arm 13 and lifts the arm 13 and hence the catch 34 clear of pin 33. (See Fig. 1.) If the armature should be attracted before the catch was 25 released, the spring 36 would be stretched and the catch swung outward around its pivot 39. This structure acts to lock the breaker arms closed whenever the interruptions in the circuit get out of synchronism 30 with the movement of the breaker arms while still leaving the armature structure free to move, and the unlocking by pin 37 permits the transmission of a retained signal only at the beginning of a revolution. It 35 will thus be seen that pin 33 coöperates with catch 34 to provide a form of disabling means for the signaling contacts, which, whenever the circuit is closed, may be held by the magnet 32 against actuation to disable 40 the signaling contacts. The engagement of the face of catch 34 above its beveled end with the pin 33 is such as to constitute a form of locking means adapted to mechanically hold said disabling means against actuation except when the breaker arm 13 has 45 been lifted, as hereinafter explained.

Fig. 5 shows the box just after it has been tripped, and with the electro-magnet 32 energized. Detent 15 has been lifted by the 50 disengaging means 16 to clear plate 19 which has rotated counterclockwise until held by pin 25. The energization of electro-magnet 32 allows pawl 28 to engage the ratchet teeth 20. Pin 27 is clear of the ratchet teeth 21 55 and will not engage any of these teeth until near the end of the revolution.

The box thus far described will transmit its signal when started, the signal-wheel revolving as many times as there are teeth in 60 the ratchet on the plate 19; but if when the home box is started the line is in use the armature of the non-interference magnet will be retracted and will lock the breaker arms, thus cutting out the home box, although 65 its signaling train and consequently

the signal wheel will continue to revolve. The retraction of the armature also will disengage pawl 28 from the ratchet teeth 20, allowing the plate 19 to swing back to the left until stopped by pin 25. When the box 70 obtains control of the line the four revolutions will be counted off anew.

The circuit changer provided for effecting the emergency ground connections is shown in this particular embodiment of 75 my invention as comprising two conducting pieces 46 and 47, mounted upon wheel 40 but insulated therefrom, and three contact springs 48, 49 and 50 (shown dotted in Fig. 1 and shown diagrammatically in Fig. 3) 80 which are so arranged in the path of movement of said pieces 46 and 47 that piece 46 makes contact with springs 48 and 49 after said ratchet wheel has moved a short distance—say two teeth—and after said wheel 85 has moved a farther distance this contact is broken and piece 47 makes contact with springs 49 and 50. The arrangement of the contacting surfaces of springs 48, 49 and 50 must be such that when wheel 40 is moving clockwise, contact is made between springs 49 and 50 before contact is broken between springs 48 and 49. A pin 57 is in such relation to the springs 58 and 59 that as the shaft 6 revolves, this pin will open 95 the circuit between the two springs 58 and 59 before and during the first part of the first closure of the contacts.

It is evident that if the box was so arranged that while the signal was being 100 transmitted the line circuit was either "open" or "grounded", a box farther from the central station on the same side of a break would not be able to receive current through its ground connection and the advancement of the ratchet 40 of the farther box would continue toward the stopping point of the box. In order to make it certain that the advancement of ratchet 40 of the farther box will not continue to that 110 point, the periods of ground connection should be so arranged that during each of one or more of the closures of the signaling contacts there is a period throughout which the ground connection will not be made 115 (that is, when the circuit is closed "metallic"), and also a period throughout which the ground connection will be made. During this "metallic" portion of the closure of the transmitting box, it is evident 120 that the farther box will receive an impulse of current through its own ground connection, and its magnet will hence be energized and the accumulation of ratchet 40 will be restored to the beginning of that 125 particular ground stage, as determined by pin 51 striking one or the other of the teeth of the holder 52.

In employing signal boxes which are arranged to transmit their signals rapidly, it 130

has been found that to secure the most efficient operation of the receiving devices, the circuit should be closed for half of the interval between strokes within a digit and 5 open for half of such interval.

In order to permit the arrangement of closures just indicated, the closure to which the extra length is added should be the first closure of a digit, and for convenience may 10 be the first digit of the round, thus only changing the length of the open circuit period between digits or between rounds. For this purpose the signal wheel 12 is so cut that the first closure is made longer than 15 any other, by providing a projection in the path of arm 13 so that it cannot drop and open the circuit as soon as it otherwise would. Spring 48 is connected to the line at one side of the box, spring 50 is connected 20 to the line at the other side of the box, and spring 49 is connected in series with springs 58 and 59 to ground. A pin 51 is secured to the ratchet wheel 40 and a holder 52 is pivoted at 53 to the frame- 25 work, and arranged to coöperate with said pin 51. The holder 52 has an extension 54 which is engaged by a pin 55 on the detent. A spring 56 tends to move the holder in the path of the pin 51. When the detent 30 15 is raised, the holder is permitted to move into the path of the pin 51 and if the ratchet wheel 40 is turned two teeth the said pin 51 passes by the end of the holder, preventing the return movement of the 35 wheel 40 as long as the detent is in elevated position. When the detent drops, the holder is disengaged and the ratchet wheel is restored to normal position. The two teeth of the holder are so spaced that one 40 will prevent the wheel 40 from moving far enough counterclockwise to carry piece 46 out of contact with springs 48 and 49, while the other is adapted to similarly prevent the wheel 40 from moving piece 47 out of contact 45 with springs 49 and 50.

Fig. 6 shows the box after there have been two ineffectual revolutions of the signal wheel, and just after the beginning of the third revolution, the electro-magnet 32 having been deënergized all of this time. Wheel 40 has been moved two teeth, bringing piece 46 into contact with springs 48 and 49. Pin 57 has moved away from spring 59, allowing that spring to close the ground connection through spring 58. Pawl 41 engages wheel 40 to hold it in position. If electro-magnet 32 should now become energized, pawl 41 would release wheel 40 but the holder 52 would prevent the wheel 40 from moving piece 46 out of contact with springs 48 and 49. Hence, if the main signaling circuit is broken, the second advancement of ratchet wheel 40 will connect the ground to the line at one side of the box, and if the magnet 32 is still deënergized, the advancement of the

wheel 40 two steps farther will connect the ground to the line at the other side of the box. In either event, the entire winding of the non-interference magnet is connected in the circuit. As the ground connection is 70 applied and transferred only at the completion of two revolutions of the signal wheel during which the electro-magnet has not been energized and the ground connection is broken during each revolution of the 75 signal wheel, it is apparent that the ground connection is only applied or transferred at the conclusion of a period during which the electro-magnet is not energized longer than the deënergized period of any connected portion of the circuit incident to the transmission of any signal. At the receiving station a ground wire may be connected as shown in Fig. 4, the battery being normally connected between the two line wires, 80 a relay being connected in each line wire, and the switch may be operated, either manually or automatically, whenever a break occurs in the line, to connect the ground to one terminal of the battery and to transfer the line normally connected to that terminal to the other terminal. By connecting the ground first to one side and then to the other at the box, both coils of the non-interference magnet are enabled to control the 90 signaling mechanism, whether the line is open at one or the other side of the box. The ground is momentarily removed by springs 58 and 59 before and during the first part of the first closure of each round 100 so that if another box beyond the home box is trying to get the line through its ground, the impulse sent to it during the first part of this closure will affect its non-interference magnet and keep the box operating 105 without permitting it to shift from its energized ground circuit.

The springs 58 and 59 must open the ground circuit before the breaker arms 13 and 14 have closed the signaling contacts, in 110 order not to cause the striking of a double blow, and the pin 33 must not be free to pass under the catch 34 until the ground circuit is closed by these springs. If the arm 13 should be lifted so high before the 115 ground circuit was closed as to allow the pin to pass the catch, it would result in the wiping out of the accumulation stored in the controlling structure, and if the arm 13 was not thereafter raised by the pin 37 120 it would result in silencing the next succeeding revolution of the signal wheel.

The operation of the mechanism shown in the annexed drawings when connected in a signaling circuit which is in normal condition and no other box in that circuit is operating is as follows:—When the mechanism is at rest the parts occupy the positions shown in Fig. 1, it being assumed that the magnet 32 and the signaling contacts 125 130

carried by the breaker arms 13 and 14 are normally shunted by means of any well known form of train shunt controlled in the usual manner by a suitable part of the mechanism, as for instance the detent 15, as will be readily understood by those skilled in the art. If, when the parts are so positioned, the disengaging means 16 is operated to "pull the box," it will lift the detent 15 and thus withdraw the pin 25 from the path of the edge 22 of the plate 19, which will be thrown to the left by the spring 24 until the projection to the left of the ratchet teeth 21 strikes the pin 25. The lifting of the detent 15 will withdraw the lug 17 from engagement with the flange 18 on the gear 4, and it is assumed that, in accordance with ordinary practice, the shunt around the magnet 32 and the signaling contacts will now be broken. The magnet 32 will now be energized and will cause the armature 31 to move to attracted position, thus swinging the pin 29 out of the path of the upper end of the pawl 28, and the weight of said pawl will therefore cause it to swing to the position where it may engage the ratchet teeth 20. (See Fig. 5.) Upon the disengagement of the lug 17 from the flange 18, the train will commence to operate, thus turning the signal wheel 12 and the plate 26 in counter clockwise direction. When the armature 31 moves to attracted position as just described, the pin 33 will be carried by the lever 30 to the left of the catch 34 without engaging said catch because the arm 13 will then be held in its extra elevated position by the engagement of the pin 37 with the pin 38, and after the train has run a short distance the pin 37 will be withdrawn from the path of the pin 38 and during the continued rotation of the signal wheel 12, its various teeth will act in succession to alternately open and close the signaling circuit at the signaling contacts carried by the breaker arms 13 and 14, and at the same time to alternately lock and unlock the armature lever 30 in a well known manner, so that whenever the circuit is broken between the contacts carried by said breaker arms, said armature lever will be locked in attracted position, but during times when the circuit is closed between said contacts said armature lever will not be held mechanically by the breaker arm 13 but will be held magnetically by the magnet 32.

The movement of the armature 31 to attracted position, which has already been described, will cause the pin 29 to swing the pawl 41 out of the path of the teeth of the ratchet wheel 40 so that, although said ratchet wheel will be moved by the engagement of the plate 26 therewith during each revolution of the signal wheel 12, said ratchet wheel will be returned to its normal

position by the spring 42 after each engagement of the plate 26 therewith. Hence neither the piece 46 nor the piece 47 will be brought into connection with the contact springs 48, 49 or 50, and therefore the alternate engagement and separation of the contact springs 58 and 59, resulting from the action of the pin 57 upon the contact spring 59 during each revolution of the signal wheel 12, will be ineffectual. 75

During each revolution of the signal wheel 12, the pin 27 will be brought into engagement with one of the teeth 21 of the plate 19, and will move said plate to the right such distance as will carry one of the teeth 20 past the engaging end of the pawl 28 so that said pawl may prevent movement of the plate 19, under the tension of the spring 24, when the pin 27 is out of engagement with the teeth 21. It will thus be seen that during the latter part of the fourth revolution of the signal wheel 12, the edge 23 of the plate 19 will be withdrawn from supporting the pin 25, and the lug 17 will thus be permitted to engage the flange 18 when the next notch in said flange is presented thereto, and thus restore the parts to their normal positions. 90

If the signaling circuit is interrupted by a so-called "plain" or "interfering" signal box while the mechanism shown in the annexed drawings is transmitting its signal, as just described, at a time when the arm 13 is so elevated as to unlock the armature lever 30, the pin 33 will act against the bevel of the catch 34 so as to slightly raise and then lock the arm 13 by passing to the right of said catch, and the pin 29 will move therewith to a position where it will cause the pawl 28 to disengage the teeth 20 and 105 where it will permit the pawl 41 to move into the path of the teeth of the ratchet wheel 40. Upon such disengagement of the pawl 28 from the teeth 20 of the plate 19, said plate will be thrown to the left by the spring 24 until the projection to the left of the ratchet teeth 21 strikes the pin 25. Thereafter during the transmission of the signal from such "plain" box, the armature 31 will move to attracted position during closures of such signal and will move to retracted position during breaks of such signal, and when in attracted position will act through the pin 29 to carry the pawl 41 out of the path of the teeth of the ratchet wheel 40, and when in retracted position will act through said pin 29 to carry the engaging end of the pawl 28 out of the path of the ratchet teeth 20, so that the advancement of the ratchet wheel 40 resulting from the engagement of the plate 26 therewith will not be retained after said plate is disengaged therefrom, and the advancement of the plate 19 resulting from the engagement of the pin 27 therewith will not be retained 110 115 120 125 130

after the disengagement of said pin from the teeth 21 of said plate.

When the armature 31 moves to attracted position, as just described, the pin 33 will 5 not cease to support the breaker arm 13 but will engage with the end of the catch 34 and swing said catch outwardly around its pivot 39. (See dotted lines Fig. 2.)

If the breaker arm 13 is raised by the 10 engagement of the pin 37 with the pin 38 during any open circuit period incident to the transmission of the signal of the "plain" box, the armature 31 will not be moved to attracted position and upon the disengagement of the pin 37 from the pin 38, the arm 15 13 will drop and thus bring the point of the catch 34 in the path of the pin 33 so as to prevent the pin 33 from passing to the left of the catch 34 until the signal wheel 12 has 20 made another revolution.

If the pin 37 acting through the pin 38 lifts the breaker arm 13 at a time when there is a closure in the signaling circuit incident to the transmission of the signal from the 25 "plain" box, the pin 33 will swing to the left of the catch 34 and thereafter the operation will be the same as the corresponding operation when two boxes are initially pulled so as to start their respective signals 30 simultaneously as will be hereinafter more fully described.

It is evident that no accumulations will be retained either by the ratchet wheel 40 or the plate 19 during the makes and breaks 35 of the signal of such "plain" box, as each closure incident to transmission of such signal will cause the armature 31 to move to attracted position and thus move the pin 29 so as to disengage the pawl 41 from the 40 ratchet wheel 40 and release any accumulation which may be stored therein, and during each break in the signal of the "plain" box, the armature 31 will move to retracted position and thus cause the pin 29 to dis- 45 engage the pawl 28 from the ratchet teeth 20 on the plate 19 and thus release any accumulation which may be stored in said plate.

When the signaling circuit is closed after 50 the signal from the "plain" box is completed, the armature 31 will cause the pin 33 to swing the catch 34 outwardly and thereby stretch the spring 36 so that the next time that the pin 37 acts through the pin 38 to lift the breaker arm 13, the spring 36 will swing the catch 34 to the right of the pin 33, and thereafter the transmission of the signal from the mechanism shown will proceed in the same manner as if it had 55 been pulled when no other box was in operation on its circuit.

If two boxes having different signal numbers but having mechanism otherwise similar to that shown in the annexed drawings 60 are connected in a closed signaling circuit

and are pulled at or about the same time, the operation of said boxes will be as follows: If one of said boxes breaks the signaling circuit slightly before the other box is in position to act to break said circuit, the pin 70 33 of said other box will move to the right of its coengaging catch 34 and thereby lock its coöperating breaker arm 13 so that the signal from the box which so first broke the signaling circuit will proceed, until completed, as when no other box is operating, and the box whose signaling contacts were closed at a time when the circuit was broken, will run without having its breaker arms 75 operatively affected by the rotation of its signal wheel, and without retaining any accumulations, either of the ratchet wheel 40 or the plate 19, until the signal of the box which first broke the circuit is completed, whereupon the box whose breaker arm was 80 85 so locked will proceed to send its signal, and its operation will be like that of a box the transmission of whose signal has been interfered with by a "plain" box, as already described. If such two boxes are pulled 90 at or about the same time and break the circuit simultaneously for the first stroke of their respective signals, the signaling contacts of both boxes may operate one or more times but upon the first occasion when one 95 box has its breaker arm 13 in elevated position during an open circuit period of the other box, it will have its breaker arm locked, and its subsequent operation will be like that of a box whose signal had been 100 interfered with by the pulling of a plain box in the circuit therewith, as already described, and the other box will proceed to transmit its signal as if it had been pulled 105 when no other box was in operation on its circuit.

If a box having the mechanism shown in the annexed drawings is pulled at a time when the signal of some other box is being transmitted over its circuit, the operation of 110 said mechanism will be the same as if the other box had been pulled at or about the same time.

When the signaling circuit is broken and the current source is grounded, as for instance by placing the switch shown in Fig. 4 in the position indicated by the dotted line, the operation of the mechanism shown in the annexed drawings, is as follows: Assuming a break in that portion of the 115 signaling circuit which connects the left hand conductor marked "Line" in Fig. 3 with the grounded current source, there being no break or operating boxes in that portion of the signaling circuit which connects the right hand conductor and said current source:—if the disengaging means 16 is operated to "pull the box" it will lift the 120 detent 15 and thus withdraw the pin 25 from the path of the edge 22 of the plate 19, 125 130

which will be thrown to the left by the spring 24 until the projection to the left of the ratchet teeth 21 strikes the pin 25. The lifting of the detent 15 will withdraw the 5 lug 17 from engagement with the flange 18 on the gear 4 and the train will commence to operate, thus turning the signal wheel 12 and the plate 26 in counter clockwise direction. The signaling circuit being open, 10 the magnet 32 will remain deenergized, and the armature 31 will remain in retracted position, so that the pin 29 will hold the pawl 28 out of engagement with the ratchet teeth 20 but will permit the pawl 41 to re- 15 main in engagement with ratchet wheel 40.

When the mechanism is started, as just described, the plate 26 will engage one of the teeth of the ratchet wheel 40, and as the signal wheel 12 rotates the ratchet wheel 40 20 will thus be moved so as to carry one of its teeth past the engaging portion of the pawl 41 before the plate 26 is disengaged from said ratchet, and after one revolution of the shaft 6, the plate 26 will again engage a 25 tooth of the ratchet wheel 40 and move another of the teeth of said ratchet past the engaging portion of the pawl 41, and such movement of said ratchet wheel will carry the pin 51 past the upper tooth or projection of the holder 52 and bring the piece 30 46 into connection with the contact springs 48 and 49. Referring to Fig. 3 it will be seen that a connection will thus be established between the left hand conductor 35 marked "Line" and the contact spring 58 and as it is assumed that an effective connection exists between the right hand conductor marked "Line" as shown in this figure and the grounded current source, it 40 is evident that current will flow from such current source through said right hand conductor and through the signaling contacts and the magnet 32, and the contact spring 48, the piece 46, the contact spring 49 and 45 the contact springs 58 and 59 as soon as the pin 57 is moved out of the path of the contact spring 59.

Before the pin 37, acting through the pin 38, has raised the breaker arm 13 to its 50 extra elevated position, the contact spring 59 will be released by the pin 57 and thereby close the circuit through the current path just described so as to energize the magnet 32, and thereupon the armature 31 will 55 move to attracted position, thus withdrawing the pawl 41 from the path of the ratchet wheel 40, and the continued rotation of the signal wheel 12 will cause the circuit to be broken and made between the contacts carried 60 by the breaker arms 13 and 14 in a well known manner and thereby transmit the signal over the portion of the signaling circuit which connects the right hand conductor shown in Fig. 3 with the grounded 65 current source. Such rotation of the sig-

nal wheel 12 will cause the plate 26 to be withdrawn from engagement with the teeth of the ratchet wheel 40 and said ratchet wheel, being now unrestrained by the pawl 41, will be moved by the spring 42 until its movement is arrested by the pin 51 striking the upper tooth or projection of the holder 52, and during succeeding revolutions of the signal wheel 12 the ratchet wheel 40 will be advanced one tooth each time the plate 26 comes into engagement therewith but will be restored by the spring 42 as soon as said plate disengages said ratchet wheel.

Just before the conclusion of the first revolution of the signal wheel 12 following the completion of the circuit through the ground, as just described, the pin 57 will engage the contact spring 59 and move it away from the contact spring 58 and while these contacts are thus separated, the signaling contacts carried by the breaker arms 13 and 14 will be brought together without unlocking the armature, thus establishing a metallic circuit connection through this mechanism during which the ground connection is not effective, and upon the further movement of the signal wheel 12 the pin 57 will be withdrawn from engagement with the contact spring 59 and thereupon the ground connection will become effective, and the armature will then be unlocked, but as the magnet 32 will now be energized, the armature 31 will be magnetically held. The further operation of the signal wheel, breaker arms, armature structure and the plate 19 will be the same as if the box had been pulled when no other box was in operation and the line was in normal condition until the edge 23 is withdrawn from the path of the pin 25, whereupon the mechanism will be brought to rest in the manner already described, and the pin 55, acting through the extension 54, will so swing the holder 52 that the teeth carried thereby will be moved out of the path of the pin 51 when the detent 15 moves to the position which brings the lug 17 in the path of the flange 18.

As the notches in the flange 18 are somewhat wider than the lug 17, the detent 15 will fall somewhat before the train comes to rest, and while the end of the breaker arm 13 lies in the path of the pin 33, so that the pin 29 will be held in such position as to hold the pawl 41 out of the path of the ratchet wheel 40 at the time the teeth carried by the holder 52 are moved out of the path of the pin 51, and thereupon the ratchet wheel 40 will be returned to its normal position by means of the spring 42.

The foregoing description of the operation of the mechanism when pulled while the signaling circuit is broken, is based upon the assumption that no other box between the current source and the box described is running, but if at the time the box described 130

is pulled, another similar box in the effective part of the circuit between it and the grounded current source is transmitting its signal through its ground connection, the operation of the box subsequently pulled will be as follows:—When the ground connection has been established through the contact springs 48 and 49, and the contact springs 58 and 59 of the second pulled box in the manner already described, the magnet 32 of said box will remain deenergized, by reason of not getting sufficient current to energize it, both during open circuit periods of the signal of such box and also during its grounded closures, and during each revolution of the signal wheel of such first pulled box, its signaling contacts will be closed at a time when its contact springs 58 and 59 are separated by the action of its pin 57, and an effective connection will thus be established between the grounded current source and the second box pulled.

As it requires two revolutions of the signal wheel 12 and plate 26 to cause the ratchet wheel 40 to be moved from the position where the pin 51 rests against the upper tooth of the holder 52 to a position where said pin 51 will be carried past the lower tooth of said holder 52, it is evident that during such two revolutions one or more of the non-grounded closures of the first box pulled, will provide energized periods for the second pulled box, each of which will cause its armature 31 to move its pin 29 to a position which will withdraw its pawl 41 from its ratchet wheel 40, and thereby permit said ratchet wheel to be moved by its spring 42 until its pin 51 is brought against the upper tooth of its holder 52.

From the foregoing it will be seen that so long as the first box pulled is transmitting its signal, the ratchet wheel 40 of the second box pulled will not be moved far enough to withdraw its contact piece 46 from the contact springs 48 and 49 and thus the second box pulled will remain in condition to transmit its signal through the ground connection which may be established through the said contact springs 48 and 49, until the first box pulled has completed the transmission of its signal and withdrawn its ground connection, whereupon the operation of the second box pulled will proceed as if it had been pulled at a time when no other box was transmitting its signal over that portion of the signaling circuit.

Assuming a break in that portion of the signaling circuit which connects the right hand conductor marked "Line" in Fig. 3 with the grounded current source, there being no break or operating boxes in that portion of the signaling circuit which connects the left hand conductor and said current source; if a box having the mechanism shown is pulled, its operation will be the

same as just described, except that when the ground connection is established between the contact springs 48 and 49 by means of the piece 46, the magnet 32 will not be energized and therefore the armature 31 will remain in retracted position so that the pawl 41 will be free to retain further accumulations imparted to the ratchet wheel 40 by the engagement of the plate 26 therewith, so that upon the further rotation of the shaft 6 the plate 26 will move the ratchet wheel 40 step by step until the pin 51 is carried past the lower tooth of the holder 52 whereupon the piece 47 will be brought into contact with the springs 49 and 50.

At the time of or shortly after the piece 47 connects the springs 49 and 50, the pin 57 will permit the contact spring 59 to connect with the contact spring 58 and thereby establish a current path from the left hand conductor marked "Line" (see Fig. 3) through the magnet 32 and the signaling contacts carried by the arms 13 and 14 to the ground, whereupon the magnet 32 will be energized and the armature 31 will move to attracted position and the mechanism will proceed to operate and transmit its signal in a manner similar to that just described, and upon the completion of such signal, the various parts will be returned to their normal positions in like manner.

If a box is pulled at a time when it is connected with the grounded current source only through the left hand conductor (see Fig. 3) and while another similar box in the effective portion of the circuit between it and the grounded current source is transmitting its signal through its ground connection, the operation of the box subsequently pulled will be as follows:—When the ground connection has been established through the contact springs 48 and 49 and the contact springs 58 and 59 of the second pulled box in the manner already described, the magnet 32 of said box will remain deenergized as it will not be included in the current path between the ground connection at such box and the grounded current source, and will not get sufficient current to energize it, and therefore its pawl 41 will remain in engagement with its ratchet wheel 40 while said ratchet wheel 40 is moved by its plate 26 until its pin 51 is carried past the lower tooth of the holder 52, whereupon the contact springs 50 and 49 will be connected by the piece 47. After the ground connection has been established through said contact springs 50 and 49, the magnet 32 of said box will remain deenergized both during open circuit periods of the signal of the first box pulled and also during its grounded closures, but during each revolution of the signal wheel of such first pulled box its signaling contacts will be closed at a time when its contact springs 58 and 59 are sepa-

rated by the action of its pin 57, and an effective connection will thus be established between the grounded current source and the second box pulled.

5 As it requires two revolutions of the signal wheel 12 and plate 26 to cause the ratchet wheel 40 to be moved from the position where the pin 51 rests against the lower tooth of the holder 52 to a position where 10 the piece 47 will be carried out of contact with the springs 50 and 49, it is evident that during such two revolutions one or more non-grounded closures of the first box pulled, will provide energized periods for the second pulled box each of which will cause its 15 armature 31 to move its pin 29 to a position which will withdraw its pawl 41 from its ratchet wheel 40, and thereby permit said ratchet wheel to be moved by its spring 42 20 until its pin 51 is brought against the upper tooth of its holder 52.

From the foregoing it will be seen that so long as the first box pulled is transmitting its signal, the ratchet wheel 40 of the second box pulled will not be moved far enough to withdraw its contact piece 47 from its contact springs 50 and 49, and thus the second box pulled will remain in condition to transmit its signal through the ground connection which may be established through the said springs 50 and 49, until the first box pulled has completed the transmission of its signal and withdrawn its ground connection, whereupon the operation of the second box pulled will proceed as if it had been pulled at a time when no other box was transmitting its signal over that portion of the signaling circuit.

If while one box is transmitting its signal through its ground connection, as already described, some other box connected in the energized portion of the circuit between the first pulled box and the grounded current source should be set in motion, such 45 second pulled box will operate in the same manner as if it had been pulled in a normal circuit which was in use for the transmission of the signal of some other box, as already described, so that the ground connection of 50 such second pulled box will not be rendered effective while closures are occurring in that portion of the circuit incident to the transmission of the signal of the first pulled box, but when the first pulled box has completed 55 the transmission of its signal and has removed its ground connection, the operation of the second pulled box will proceed in the same manner as if such box had been pulled on a broken line at a time when no other 60 box was engaged in the transmission of its signal.

Assuming a break in the portion of the signaling circuit which connects the right hand conductor marked "Line" in Fig. 3 65 and a second break in the portion of the

signaling circuit which connects the left hand conductor marked "Line" in said figure with the grounded current source:—if a box, having the mechanism shown, is pulled, its operation will be the same as already described except that while the ground connections are established the magnet 32 will not be energized, and therefore the armature 31 will remain in retracted position so that the pawl 41 will be free to retain further accumulations imparted to the ratchet wheel 40 by the engagement of the plate 26 therewith, so that, upon the further rotation of the shaft 6, the plate 26 will move the ratchet wheel 40 step by step until the pin 45 is carried against the plate 19, and has moved said plate against the tension of its spring 24 until the edge 23 is withdrawn from the path of the pin 25 whereupon the operation of the box will be arrested in the manner already described.

The importance of having the closures divided into non-grounded and grounded parts is illustrated by the foregoing description of the operation of the mechanism shown in the annexed drawings, and the further importance of having the non-grounded part of divided closures precede the grounded part will be recognized when it is considered that alarm receiving or indicating devices, employed in connection with signal boxes of the character described, are usually arranged to act in response to breaks in the circuit. If, for instance, the divided closures were arranged so that the ground was effective during the first part and ineffective during the second part thereof, in order to have the signal strokes separated by the proper intervals when the box was transmitting over a normal all-metallic circuit, the spacing would have to be measured from the metallic breaks, and if so spaced, the corresponding intervals would be different if such a box was working through its ground connection. While the confusion which might result from such different intervals between the breaks following divided and non-divided closures might be overcome by arranging the mechanism so that all closures would be divided 115 closures, a source of confusion would still exist in that if a box was transmitting a signal through its ground connection and such ground connection was effective during the first part of all closures, the pulling of another similar box connected by the same conductor, and located at a point more distant from the grounded current source, might result in the development of the ground connection at such more distant box at such a 120 time between two divided closures that the effective circuit break of one closure would be the termination of its grounded part while the effective break following the next closure would only come at the termination 125 130

of its metallic part. All signal box mechanisms should therefore be so constructed that divided closures will be so arranged that the non-grounded part will precede the grounded part.

5 From the above description of the operation of the circuit changer it will be seen that the non-interference magnet and the signaling contacts of the box are first connected in the metallic circuit. If such metallic circuit remains continuously deenergized for a time longer than the longest time between energized periods of any signal, the continued retraction of the non-interference armature will permit the circuit changer to be held in such position that it will be moved by the train to connect the non-interference magnet and the signaling contacts in a ground circuit from one line wire. If this ground circuit remains continuously deenergized for a time longer than the longest time between energized periods incident to the transmission of any signal in such circuit, the continued retraction of the non-interference armature will permit the circuit changer to be held in such position that it will be moved by the train to connect the non-interference magnet and the signaling contacts in a ground circuit from the other line wire. If this second ground circuit remains continuously deenergized for a time longer than the longest time between energized periods incident to the transmission of any signal in such circuit, the continued retraction of the non-interference armature will permit the ratchet wheel to be held in such position that it will be moved by the train to cause the controlling structure to be withdrawn to permit the detent to stop the train and restore the metallic circuit through the box.

I claim the following:—

1. In a signal box having three terminals, an electromagnet, and signaling contacts; means for opening and closing said contacts between two of said terminals, and means controlled by said magnet for connecting the third terminal to one of said two terminals during a part only of the duration of each of one or more of the closures of said contacts.

2. In a signal box having three terminals, an electromagnet, and signaling contacts; means for opening and closing said contacts between two of said terminals, and means for connecting the third terminal to one of said two terminals during a part only of the duration of each of one or more of the closures of said contacts, said means being so controlled by said magnet that said connection will be made only after the expiration of a time longer than the longest time between any two consecutive divided closures of any signal.

3. In a signal box having three terminals,

an electromagnet, a train, and signaling contacts; means for opening and closing said contacts between two of said terminals, means controlled by said magnet for connecting the third terminal to one of said two terminals, and means operated by the train for arranging the duration of the periods of such connection so that during each of one or more of the closures of said contacts there shall be a period throughout which said connection will not be made and also a period throughout which it will be made.

4. In a signal box having three terminals, an electromagnet, a train, and signaling contacts; means for opening and closing said contacts between two of said terminals, means for connecting the third terminal to one of said two terminals, and means operated by the train for arranging the duration of the periods of such connection so as to divide each of one or more of the closures of said contacts so that during each of such divided closures there shall be a period throughout which said connection will not be made and also a period throughout which it will be made, said second named means being so controlled by said magnet that said connection will be made only after the expiration of a time longer than the longest time between any two consecutive divided closures of any signal.

5. In a signal box having three terminals, an electromagnet, signaling contacts, a train, and a detent therefor; means for opening and closing said contacts between two of said terminals, means controlled by said magnet for connecting the third terminal to said contacts during a part only of the duration of each of one or more of the closures of said contacts.

6. In a signal box having three terminals, an electromagnet, signaling contacts, a train, and a detent therefor; means for opening and closing said contacts between two of said terminals, means for connecting the third terminal to said contacts during a part only of the duration of each of one or more of the closures of said contacts, said second named means being so controlled by said magnet that said connection will be made only after the expiration of a time longer than the longest time between any two consecutive divided closures of any signal, and controlling structure governed by said magnet for rendering said detent effective only after the magnet has not been energized during a time longer than the longest time between any two consecutive divided closures of any signal.

7. In a signal box having three terminals, an electromagnet, signaling contacts, a train, and a detent therefor; means for opening and closing said contacts between two of said terminals, means controlled by said

magnet for connecting the third terminal to said contacts, means operated by the train for arranging the duration of the periods of such connection so as to divide each of one 5 or more of the closures of said contacts so that during each of such divided closures there shall be a period throughout which said connection will not be made and also a period throughout which it will be made, 10 and controlling structure governed by said magnet for rendering said detent effective only after the magnet has not been energized during a time longer than the longest time between any two consecutive divided closures of any signal.

8. In a signal box having three terminals, an electromagnet, and signaling contacts; means for opening and closing said contacts between two of said terminals, means for 20 connecting the third terminal to said contacts, means for arranging the duration of the periods of such connection so as to divide each of one or more of the closures of said contacts so that during each of such 25 divided closures there shall be a period throughout which said connection will not be made and also a period throughout which it will be made, said second named means being so controlled by said magnet that said 30 connection will be made only after the expiration of a time longer than the longest time between any two consecutive divided closures of any signal.

9. In a signal box having three terminals, 35 an electromagnet, a train, and signaling contacts; means for opening and closing said contacts between two of said terminals, means controlled by said magnet for connecting the third terminal to said contacts during a part only of the duration of each of 40 one or more of the closures of said contacts, disabling means for the signaling contacts adapted to be held by said magnet against actuation, and locking means adapted 45 to be so operated by said train that it will mechanically hold said disabling means against actuation except during periods throughout which said connection may be made.

10. In a signaling system, the combination 50 of two line wires, current supply mechanism and translating mechanism connected between said line wires and ground, a signal box having an electromagnet, and signaling contacts, and means whereby said magnet is 55 enabled to test for current to ground during a part only of the duration of each of one or more of the closures of said contacts.

11. In a signal box having three terminals, 60 an electromagnet, signaling contacts, a train, and a detent therefor; means for opening and closing said contacts between two of said terminals, means for connecting the third terminal to said contacts, means

operated by the train for arranging the duration of the periods of such connection as to divide each of one or more of the closures of said contacts so that during each of such divided closures there shall be a period 65 throughout which said connection will not be made and also a period throughout which it will be made, said second named means being so controlled by said magnet that said connection will be made only after the expiration of a time longer than the longest 70 time between any two consecutive divided closures of any signal, and controlling structure governed by said magnet for rendering said detent effective only after the magnet has not been energized during a time longer 75 than the longest time between any two consecutive divided closures of any signal.

12. In a signal box having three terminals, an electromagnet, and signaling contacts; means for opening and closing said 80 contacts between two of said terminals, means controlled by said magnet for establishing a connection from said contacts to the third terminal and means for arranging the duration of the periods of such connection 85 so that during each of one or more of the closures of said contacts there shall be a period throughout which said connection will not be made and also a period throughout 90 which it will be made.

13. In a signal box having three terminals, an electromagnet, a train, and signaling contacts; means for opening and closing said contacts between two of said terminals, means controlled by said magnet for connecting the third terminal to one of said 100 two terminals, and means operated by the train for arranging the duration of the periods of such connection so that each of one or more of the closures of said contacts 105 will be divided into two parts and so that throughout the first of said two parts said connection will not be made and so that said connection will be made throughout the second of said two parts.

14. In a signal box having three terminals, an electromagnet, a train, and signaling contacts; means for opening and closing said contacts between two of said terminals, means for connecting the third terminal to 110 one of said two terminals, and means operated by the train for arranging the duration of the periods of such connection so that each of one or more of the closures of said contacts will be divided into two parts 115 and so that throughout the first of said two parts said connection will not be made and so that said connection will be made throughout the second of said two parts, said second named means being so controlled 120 by said magnet that said connection will be made only after the expiration of a time longer than the longest time between any 125

two consecutive divided closures of any signal.

15. In a signal box having three terminals, an electromagnet, signaling contacts, a train, and a detent therefor; means for opening and closing said contacts between two of said terminals, means controlled by said magnet for connecting the third terminal to said contacts during a part only of the duration of each of one or more of the closures of said contacts.

5 10 15

16. In a signal box having three terminals, an electromagnet, signaling contacts, a train, and a detent therefor; means for opening and closing said contacts between two of said terminals, means controlled by said magnet for connecting the third terminal to said contacts, means operated by the train 20 25 30 35

for arranging the duration of the periods of such connection so that each of one or more of the closures of said contacts will be divided into two parts and so that throughout the first of said two parts said connection will not be made and so that said connection will be made throughout the second of said two parts, and controlling structure governed by said magnet for rendering said detent effective only after the magnet has not been energized during a time longer than the longest time between any two consecutive divided closures of any signal.

17. In a signal box having three terminals, an electromagnet, signaling contacts, a train, and a detent therefor; means for opening and closing said contacts between two of said terminals, means for connecting the third terminal to said contacts, means 40 45 50 55 60

operated by the train for arranging the duration of the periods of such connection so that each of one or more of the closures of said contacts will be divided into two parts and so that throughout the first of said two parts said connection will not be made and so that said connection will be made throughout the second of said two parts, said second named means being so controlled by said magnet that said connection will be made only after the expiration of a time longer than the longest time between any two consecutive divided closures of any signal, and controlling structure governed by said magnet for rendering said detent effective only after the magnet has not been energized during a time longer than the longest time between any two consecutive divided closures of any signal.

18. In a signal box having three terminals,

an electromagnet and signaling contacts; means for opening and closing said contacts between two of said terminals, and means controlled by said magnet for connecting the third terminal to said contacts during a part only of the duration of each of one or more of the closures of said contacts.

19. In a signal box having three terminals, an electromagnet, and signaling contacts; means for opening and closing said contacts between two of said terminals, and means for connecting the third terminal to said contacts during a part only of the duration of each of one or more of the closures of said contacts, said second-named means being so controlled by said magnet that said connection will be made only after the expiration of a time longer than the longest time between any two consecutive divided closures of any signal.

20. In a signal box having three terminals, an electromagnet and signaling contacts; means for opening and closing said contacts between two of said terminals, means controlled by said magnet for establishing a connection from said contacts to the third terminal, and means for arranging the duration of the periods of such connection so that each of one or more of the closures of said contacts will be divided into two parts and so that throughout the first of said two parts said connection will not be made and so that said connection will be made throughout the second of said two parts.

21. In a signal box having three terminals, an electromagnet, and signaling contacts; means for opening and closing said contacts between two of said terminals, means for connecting the third terminal to said contacts, means for arranging the duration of the periods of such connection so that each of one or more of the closures of said contacts will be divided into two parts and so that throughout the first of said two parts said connection will not be made and so that said connection will be made throughout the second of said two parts, said second named means being so controlled by said magnet that said connection will be made only after the expiration of a time longer than the longest time between any two consecutive divided closures of any signal.

22. In a signal box having mechanism adapted for the transmission of a signal comprising one or more groups of impulses; three terminals, an electromagnet, signaling contacts, means for opening and closing said contacts between two of said terminals, and means controlled by said magnet for connecting the third terminal to one of said two terminals during a part only of the duration of the closure preceding the first break of each of said groups.

23. In a signal box having mechanism adapted for the transmission of a signal comprising one or more groups of impulses; three terminals, an electromagnet, signaling contacts, means for opening and closing said contacts between two of said terminals, and means for connecting the third terminal to one of said two terminals during a part only of the duration of the closure preceding the first break of each of said groups, said second named means being so controlled by said magnet that said connection will be made only after the expiration of a time longer than the longest time between any two consecutive divided closures of any signal.

24. In a signal box having mechanism adapted for the transmission of a signal comprising one or more groups of impulses; three terminals, an electromagnet, a train, signaling contacts, means for opening and closing said contacts between two of said terminals, means controlled by said magnet for connecting the third terminal to one of said two terminals and means operated by the train for arranging the duration of the periods of such connection so that during the closure preceding the first break of each of said groups there shall be a period throughout which said connection will not be made and also a period throughout which it will be made.

25. In a signal box having mechanism adapted for the transmission of a signal comprising one or more groups of impulses; three terminals, an electromagnet, a train, signaling contacts, means for opening and closing said contacts between two of said terminals, means for connecting the third terminal to one of said two terminals and means operated by the train for arranging the duration of the periods of such connection so that during the closure preceding the first break of each of said groups there shall be a period throughout which said connection will not be made and also a period throughout which it will be made, said second named means being so controlled by said magnet that said connection will be made only after the expiration of a time longer than the longest time between any two consecutive divided closures of any signal.

26. In a signal box having mechanism adapted for the transmission of a signal comprising one or more groups of impulses; three terminals, an electromagnet, signaling contacts, a train, a detent therefor, means for opening and closing said contacts between two of said terminals, means controlled by said magnet for connecting the third terminal to said contacts during a part only of the duration of the closure preceding the first break of each of said groups,

and controlling structure governed by said magnet for rendering said detent effective only after the magnet has not been energized during a time longer than the longest time between any two consecutive divided closures of any signal.

27. In a signal box having mechanism adapted for the transmission of a signal comprising one or more groups of impulses; three terminals, an electromagnet, signaling contacts, a train, a detent therefor, means for opening and closing said contacts between two of said terminals, means for connecting the third terminal to said contacts during a part only of the duration of the closure preceding the first break of each of said groups, said second named means being so controlled by said magnet that said connection will be made only after the expiration of a time longer than the longest time between any two consecutive divided closures of any signal, and controlling structure governed by said magnet for rendering said detent effective only after the magnet has not been energized during a time longer than the longest time between any two consecutive divided closures of any signal.

28. In a signal box having mechanism adapted for the transmission of a signal comprising one or more groups of impulses; three terminals, an electromagnet, signaling contacts, a train, a detent therefor, means for opening and closing said contacts between two of said terminals, means controlled by said magnet for connecting the third terminal to said contacts, means operated by the train for arranging the duration of the periods of such connection so that during the closure preceding the first break of each of said groups there shall be a period throughout which said connection will not be made and also a period throughout which it will be made, and controlling structure governed by said magnet for rendering said detent effective only after the magnet has not been energized during a time longer than the longest time between any two consecutive divided closures of any signal.

29. In a signal box having mechanism adapted for the transmission of a signal comprising one or more groups of impulses; three terminals, an electromagnet, signaling contacts, a train, a detent therefor, means for opening and closing said contacts between two of said terminals, means operated by the train for arranging the duration of the periods of such connection so that during the closure preceding the first break of each of said groups there shall be a period throughout which said connection will not be made and also a period throughout which it will be made, said second named means being so controlled by said magnet that said connection will be made

- only after the expiration of a time longer than the longest time between any two consecutive divided closures of any signal, controlling structure governed by said magnet for rendering said detent effective only after the magnet has not been energized during a time longer than the longest time between any two consecutive divided closures of any signal.
30. In a signal box having mechanism adapted for the transmission of a signal comprising one or more groups of impulses; three terminals, an electromagnet, signaling contacts, means for opening and closing said contacts between two of said terminals, and means controlled by said magnet for connecting the third terminal to said contacts during a part only of the duration of the closure preceding the first break of each of said groups.
31. In a signal box having mechanism adapted for the transmission of a signal comprising one or more groups of impulses; three terminals, an electromagnet, signaling contacts, means for opening and closing said contacts between two of said terminals, means for connecting the third terminal to said contacts during a part only of the duration of the closure preceding the first break of each of said groups, said second named means being so controlled by said magnet that said connection will be made only after the expiration of a time longer than the longest time between any two consecutive divided closures of any signal.
32. In a signal box having mechanism adapted for the transmission of a signal comprising one or more groups of impulses; three terminals, an electromagnet, signaling contacts, means for opening and closing said contacts between two of said terminals, means controlled by said magnet for connecting the third terminal to said contacts, and means for arranging the duration of the periods of such connection so that during the closure preceding the first break of each of said groups there shall be a period throughout which said connection will not be made and also a period throughout which it will be made.
33. In a signal box having mechanism adapted for the transmission of a signal comprising one or more groups of impulses; three terminals, an electromagnet, signaling contacts, means for opening and closing said contacts between two of said terminals, means for connecting the third terminal to said contacts, and means for arranging the duration of the periods of such connection so that during the closure preceding the first break of each of said groups there shall be a period throughout which said connection will not be made and also a period throughout which it will be made, said second
- named means being so controlled by said magnet that said connection will be made only after the expiration of a time longer than the longest time between any two consecutive divided closures of any signal.
34. In a signal box having mechanism adapted for the transmission of a signal comprising one or more groups of impulses; three terminals, an electromagnet, a train, signaling contacts, means for opening and closing said contacts between two of said terminals, means controlled by said magnet for connecting the third terminal to said contacts during a part only of the duration of the closure preceding the first break of each of said groups, disabling means for the signaling contacts adapted to be held by said magnet against actuation, and locking means adapted to be so operated by said train that it will mechanically release said disabling means during periods throughout which said connection may be made.
35. In a signaling system, the combination of two line wires, current supply mechanism and translating mechanism connected between said line wires and ground, a signal box having mechanism adapted for the transmission of a signal comprising one or more groups of impulses, an electromagnet, signaling contacts, and means whereby said magnet is enabled to test for current to ground during a part only of the duration of the closure preceding the first break of each of said groups.
36. In a signal box having three terminals, and a current path connected between two of said terminals and serially including an electromagnet and signaling contacts; a train, and means operated by said train and controlled by said magnet for making a connection between the third terminal and one end of said current path only after the magnet has remained deenergized for a period longer than the longest period of deenergization incident to the transmission of any signal.
37. In a signal box having three terminals, and a current path connected between two of said terminals and serially including an electromagnet and signaling contacts; a train, a detent therefor, means operated by said train and controlled by said magnet for making a connection between the third terminal and one end of said current path, and controlling structure governed by said magnet for rendering said detent effective only after the magnet has remained deenergized subsequent to the making of said connection for a period longer than the longest period of deenergization of said magnet incident to any signal.
38. In a signal box having three terminals, and a current path connected between two of said terminals and serially including

an electromagnet and signaling contacts; a train, a detent therefor, means operated by said train and controlled by said magnet for making a connection between the third terminal and one end of said current path only after the magnet has remained deenergized for a period longer than the longest period of deenergization incident to the transmission of any signal, and controlling structure governed by said magnet for rendering said detent effective only after the magnet has remained deenergized subsequent to the making of said connection for a period longer than the longest period of deenergization of said magnet incident to any signal.

39. In a signal box having three terminals, and a current path connected between two of said terminals and serially including an electromagnet and signaling contacts; a train, means operated by said train and controlled by said magnet for making a connection between the third terminal and one end of said current path only after the magnet has remained deenergized for a period longer than the longest period of deenergization incident to the transmission of any signal and for making a connection between the third terminal and the other end of said current path only after the magnet has remained deenergized subsequent to the making of said first named connection for a period longer than the longest period of deenergization of said magnet incident to any signal.

40. In a signal box having three terminals, and a current path connected between two of said terminals and serially including an electromagnet and signaling contacts; a train, a detent therefor, means controlled by said magnet for making a connection between the third terminal and either one or the other of the ends of said current path, and controlling structure governed by said magnet for rendering said detent effective only after the magnet has remained deenergized subsequent to the making of said connections for a period longer than the longest period of deenergization of said magnet incident to any signal.

41. In a signal box having three terminals, and a current path connected between two of said terminals and serially including an electromagnet and signaling contacts; a train, a detent therefor, means operated by said train and controlled by said magnet for making a connection between the third terminal and one end of said current path only after the magnet has remained deenergized for a period longer than the longest period of deenergization incident to the transmission of any signal and for making a connection between the third terminal and the other end of said current path only after the magnet has remained deenergized subsequent to the making of said first named connection for a period longer than the longest period of deenergization of said magnet incident to any signal, and controlling structure governed by said magnet for rendering said detent effective only after the magnet has remained deenergized subsequent to the making of the second of said connections for a period longer than the longest period of deenergization of said magnet incident to any signal.

42. In a signal box having an electromagnet, signaling contacts, a signal wheel, a train, and a detent therefor; controlling structure governed by said magnet for rendering said detent effective after five revolutions of the signal wheel, means controlled by said magnet for making a connection between ground and one side of said contacts and said magnet after one revolution of the signal wheel and for making a connection between ground and the other side of said contacts and said magnet after three revolutions of the signal wheel, said ground connection being ineffective during a part of one of the closures of said signaling contacts incident to each revolution of the signal wheel.

In witness whereof, I hereunto subscribe my name, this 8th day of August, A. D., 1913.

CLARENCE E. BEACH.

Witnesses:

W. R. GANDY,
W. T. KENDALL BROWN.
